UNITED STATES PATENT OFFICE.

JAMES I. FLANAGEN, OF PHILADELPHIA, PENNSYLVANIA.

DESIGN FOR A PLATE FOR STOVE-PIPE FLUES, &c.

SPECIFICATION forming part of Design No. 17,457, dated July 19, 1887.

Application filed May 31, 1887. Serial No. 239,892. Term of patent 7 years.

To all whom it may concern:

Be it known that I, JAMES I. FLANAGEN, a citizen of the United States, residing in the city and county of Philadelphia, State of Pennsylvania, have invented and produced a new and original Design for a Plate for a Stove-Pipe Flue, Collar-Stopper, &c., of which the following is a specification, reference being had to the accompanying drawing, forming part 5 thereof.

The leading features of my design for a plate for a stove-pipe flue, &c., are radial corrugations on the rim of the plate and series of corrugations on the breast.

15 A represents a plate having radial corrugations *a* on the rim and a series of corrugations, *b*, on the breast *B*. Each series or group of corrugations *b* has its members of different

lengths, and they branch out from the inner rim of the breast.

20

The central field, *C*, of the plate is plain. I claim—

1. The design for a plate for a stove-pipe flue, &c., herein shown and described, comprising a breast with corrugations in groups, 25 and a rim having radial corrugations.

2. A design for a plate for a stove pipe flue, &c., having a breast with corrugations thereon, said corrugations being in groups, the members of which branch or spread out, as shown 30 and described.

JAMES I. FLANAGEN.
